UNITED STATES PATENT OFFICE.

JAMES O. ENGLE, OF RANSOM, KANSAS.

FOLDING SHIPPING-CRATE.

1,138,096.

Specification of Letters Patent.

Patented May 4, 1915.

Application filed May 16, 1914. Serial No. 839,112.

To all whom it may concern:

Be it known that I, JAMES O. ENGLE, a citizen of the United States, residing at Ransom, in the county of Ness and State of

5 Kansas, have invented certain new and useful Improvements in Folding Shipping-Crates; and I do hereby declare the following to be a full, clear, and exact description of the invention, such as will enable others 10 skilled in the art to which it appertains to make and use the same.

My invention refers to a shipping crate of the folding or collapsible type, as will be apparent from the following specification 15 reference being had to the accompanying drawings which are made a part of this application in which,

Figure 1 is a top plan view. Fig. 2 is a side elevation. Fig. 3 is an end elevation. 20 Fig. 4 is a longitudinal section as indicated by dotted lines *a—a* Fig. 1. Fig. 5 is a transverse section as indicated by dotted lines *b—b* Fig. 1. Fig. 6 is a transverse section of a folded crate. Fig. 7 is a plan view 25 of the end grooved retaining members. Fig. 8 is a plan view of the center or partition, grooved retaining members, Fig. 9 is a cross section of Fig. 7.

In the detailed description of my invention, numerals will be used to designate the 30 various parts, the same numeral being used throughout the various views to indicate the same part.

My invention comprises a shipping crate, 35 the body portion 1 being rectangular in form and of a size determined by the purpose for which it is required, a plurality of members 2 of uniform size are hingedly mounted on the upper side of the said body portion in 40 a transverse position so that two of said members will serve as ends for the crate and the remainder as partitions, when the crate is folded these members lie flat on the body portion.

45 Along the sides of the body portion and extending upward at right angles thereto, narrow strips 3 of wood are fastened, the ends thereof being connected by strips of galvanized iron 4 the lower edge of which 50 is nailed to the end of the body portion.

Hingedly attached to the strips 3 are

members 5, corresponding in length to that of the body portion and of a width determined by the width of the members 2, serving as sides for the crate.

Hingedly attached to each of the side members 5 and folding in the same direction is a member 6 corresponding in length to the side member to which it is attached, its width being determined by the length of the member 2 said member serving as part of the top or lid of the crate and extending to the center of said member 2 when it is in an upright position. Across the under side of the member 6 are carried metallic fastening members 7 having a groove of sufficient width to allow the top edge of the members 2 to enter therein its entire length, thus forming a stay and support for the said members 2 when in operative position and adding rigidity and stability to the crate when set up. Said fastening members are provided with flanges by which they are fastened in place.

The side member 5 and the top member 6 are made in duplicate a pair being required to form a complete crate. The two parts of the member 6 are provided with a hasp and staple for the purpose of fastening or locking the top or lid.

The fastening members carried by the top are formed by folding sheet metal, preferably galvanized iron, back upon itself to form two ribs extending parallel to each other, the space between the ribs constituting the groove.

The inner flanges of the members 7 at the ends of the crates are provided with ears formed by slitting said inner flanges and bending the slit portions at right angles, 90 said ears extending below and being secured to the side rails of the members 6 while the outer flanges extend in the same plane as the outside of the rib and are secured to the outer faces of the end rails of the members 6.

The fastening members used in connection with the partitions of the crate are formed similarly to those used on the ends, except that the ends of the flanges on both sides are slit and the slit portions extended at right angles to the plane of the ribs to

form ears, which ears are likewise secured to the under face of the side rails of the members 6 and by providing these ears the members 7 can be extended the full width 5 of the members 6.

When the crate is intended for the shipment of live poultry, etc., the various members 2-5 and 6 are formed of a frame covered with mesh wire, and a small opening 10 with a hinged closure is provided in the member 6 to permit of the removal of the contents of the crate while in a set up condition, the closure or door being hinged to a cross bar forming the walls of the opening, the opposite edge of the closure having 15 a hasp hinged thereto, said hasp being employed for locking the door in closed position and also for locking the two sections of the members 6 together thereby dispensing 20 with an additional hasp for this purpose.

To collapse the crate the top members 6 are raised to a perpendicular position on the edge of the member 5 and then the members 2 are folded down upon the member 1, then 25 the members 5 and 6 from one side of the crate still in their extended position are folded down upon the members 2 and then the members 5 and 6 from the opposite side of the crate are folded down upon the first 30 pair of members 5 and 6 already folded down, thus forming a compact package for shipment which will occupy very much less space than when in a set up position, and also providing a shipping crate that may be 35 used for live poultry, etc., or for any class of merchandise where it may be desired to preserve the cases for future shipments.

While I have described in the foregoing specifications and illustrated in the accompanying drawings the preferred construction and combination of parts deemed necessary to materialize my invention, I desire it to be understood that I wish to comprehend in this application all substantial equivalents and substitutes which may be considered as falling fairly within the scope of my invention, I do not therefore wish to be 45

confined strictly to the exact showing herein presented.

Having thus fully described my invention 50 what I desire to secure by Letters Patent is:-

1. In a shipping crate, a base member, side, end and partition members hinged thereto and adapted to fold down upon said base, a top member carrying a plurality of grooved members adapted to receive the contiguous edges of the said end and partition walls and extending the full length of said end and partition walls, said grooved members each consisting of a piece of sheet metal bent upon itself to form a groove and anchoring flanges, the ends of said flanges having ears formed integral therewith and extended at right angles thereto. 65

2. In a shipping crate, a body or base portion, side strips along the edges of said body portion, metallic strips along the ends of the body portion and secured to said side strips, side members hinged to the side 70 strips, end and partition members hinged to the body portion, said side, end and partition members being adapted to fold down on said body portion, a pair of top members hinged to said side members, grooved members on the under faces of said top members adapted to receive the contiguous edges of said end and partition walls, said groove members extending the full length of said end and partition walls, doors hingedly secured to parts of said top members adapted to form closures for openings therein and hasps hingedly secured to said doors adapted to engage parts of the top members and lock said top members and doors in closed 80 position.

In testimony whereof I have signed my name to this specification in the presence of two subscribing witnesses.

JAMES O. ENGLE.
